METHOD OF MAKING A FLANGED VALVE
HOUSING

James Hall Taylor, Oak Park, Ill.

Application October 2, 1935, Serial No. 43,193

4 Claims. (Cl. 29—157.1)

This invention relates to valve housings, and has to do with a valve housing, such as a gate valve housing, provided at its ends with bolting flanges for bolting to pipe ends.

5 In general, my invention is directed to a valve housing of simple construction, light weight and adequate mechanical strength, provided at its ends with bolting flanges, and to a method for producing the housing expeditiously and at low 10 cost. Further objects and advantages of my invention will appear from the detail description.

In the drawings:—

Figure 1 is a sectional view through two cooperating dies and a partially formed blank therebetween, illustrating a preliminary step in forging one of the sections of the housing in accordance with the method of my invention;

Figure 2 is a sectional view through the blank of Figure 1 and a die and a cooperating extruding punch illustrating a succeeding step in the method of my invention;

Figure 3 is a sectional view through a pair of upper forming dies and a lower supporting block illustrating a further step of the method of my invention, the partially formed blank being shown in section and certain parts being shown in elevation;

Figure 4 is a sectional view through an upper pair of forming dies and a lower forming die, illustrating a succeeding step in the method of my invention, the guide stem being shown in elevation;

Figure 5 is a sectional view through a pair of upper forming dies and a lower die, showing the use of the cutting die for removing the metal from the closed end of the partially formed valve housing section, the guide stem and the cutting die being shown in elevation;

Figure 6 is a fragmentary sectional view taken 40 substantially on line 6—6 of Figure 3;

Figure 7 is a sectional view taken substantially on line 7—7 of Figure 4, on a reduced scale;

Figure 8 is a central lengthwise sectional view through a valve housing produced in accordance 45 with my invention;

Figure 9 is an end view, partly broken away and in section, of a completed valve structure embodying my invention, this view being on a reduced scale.

50 In my copending application for Valve housing and method of making same, Serial No. 17,655, filed April 22, 1935, now Patent Number 2,065,035, granted December 22, 1936, I have disclosed a valve housing formed of two sections adapted for welding to pipe ends, the sections of

the housing being welded together on the median transverse plane of the housing. The instant invention is directed to a valve housing similar to that of my co-pending application, but provided with end bolting flanges whereby the ends of the housing may be bolted to flanged pipe ends.

The valve housing is formed in two complementary sections which divide the housing at the median transverse plane thereof and are welded together at their inner ends. Preferably, the sections of the housing are formed by forging from steel or other metal suitable for the purpose. A billet of suitable size is first forged to produce a cup-like blank *c* from which projects a flange *a* inclined transversely of the blank, as shown in Figure 1. This is accomplished by suitably shaped cooperating upper and lower dies *b* and *d*, respectively, having relative movement one toward and away from the other, the upper die conveniently being the movable die. The recess formed in blank *c* flares upward, as shown in Figure 1, and the portion of the blank below this recess forms a mass of metal of considerably greater height than the depth of the recess, the billet from which the blank is formed being of suitable size for this purpose.

Blank *c*, formed as above described, is then placed in a cooperating recess in a die *e* and a cylindrical extruding punch *f* of less diameter than the upper portion of the recess in blank *c*, 30 is inserted downward into the blank *c*, the latter being so disposed that the punch *f* is in contact with and parallel to the side of the recess of the blank adjacent the upper portion of flange *a*, as shown in Figure 2. The die *e* of Figure 2 may be 35 the die *d* of Figure 1, positioned as in Figure 2, or it may be another die. The punch *f* is then moved downward into the blank so as to extrude the metal thereof upward along punch *f*, between the latter and the confining wall of the recess of die *e*, as shown in Figure 2. In this manner, the blank *c* is extended so as to produce a relatively 40 elongated hub *h*, the upper portion of which, at one side thereof, is inclined upward and outward away from punch *f*, as shown, the upper end of 45 the hub being inclined transversely thereof in the same direction as, but to a less extent than, flange *a*. The blank, as thus formed, is provided at its lower end with a solid mass of metal *g* of considerable depth.

50 The blank shown in Figure 2 is then acted upon by upper and lower dies *k* and *m*, respectively, in such manner as to shape flange *a* to form one-half of the body of the desired housing, as in Figures 3 and 6. The upper die *k* has a depend- 55

ing guide stem *o* of a size to fit within hub *h* of the blank, when the dies are closed, and the lower die *m* is in the form of a split die comprising two sections semi-circular in plan, as shown in Figure 7, these sections being moved toward and away from each other by suitable known means. When the sections of die *m* are closed, this die fits snugly about hub *h* of the blank and effectively confines the latter against radial distortion, in conjunction with the guide stem *o*, during forming of the flange *a* to desired shape. During this operation, die *m* rests upon a lower block *p* provided therewith through an opening *r* of a size to accommodate the lower portion of the blank including the mass of metal *g*.

After the blank has been formed as in Figure 3, block *p* is replaced by a bottom die *s* provided in its upper face with a cylindrical recess *t* disposed concentric with hub *h* of the blank, and the mass of metal *g* is then smashed down by moving the dies *k* and *m*, together with the guide stem *o* and the intervening blank, as a unit, toward the bottom die *s*. The mass of metal *g* is thus spread radially in the recess *t* so as to form an annular flange *v* projecting radially outward from hub *h* of the blank, and a disc *w* which closes the lower end of the hub. Bottom die *s* is then replaced by a die *x* having a constriction *y* of the same diameter as the interior of hub *h* of the blank and an opening *z* of greater diameter than and extending downward from constriction *y*. Die *x* is disposed so that flange *v* of the blank seats in recess *t* in the upper face of this die, constriction *y* and opening *z* of die *x* being disposed coaxially with hub *h* of the blank and guide stem *o*. The dies *k* and *m* are then separated sufficiently to withdraw stem *o* from the blank and permit introduction of a cutting disc or die *i* into the hub *h*, after which the dies *k* and *m* are again closed, conveniently by moving die *k* downward toward die *m*, the latter die and the blank being supported by the bottom die *x*. In this second closing of the dies, stem *o* contacts cutting die *i*, forcing the latter downward and thereby cutting disc *w* from the lower end of hub *h*, as in Figure 5. This completes the housing section, except as to the removal of such flash metal as may remain on the flange *v* or other portions of the housing section.

I provide two housing sections *l*, produced as above, each of which constitutes one-half of the valve housing and which, in the completed housing, are welded together at their inner ends, the line of weld corresponding to the transverse median plane of the housing. Each of the sections *l* comprises a tubular hub *2* having at its outer end an integral flange *3* for bolting to a cooperating flange of a pipe end, and a flange *4*, adjacent the inner end of the hub, formed integrally therewith and shaped to provide one-half *5* of the body of the housing. Each section *l* also comprises an integral valve seat element *6* which projects inward beyond flange *4* and is disposed at a downward and inward inclination 65 to the hub, as in Figure 8.

The end of each of the seat elements *6* constitutes a valve seat to which I apply a wear and corrosion resistant surface *6a*, this surface being in the form of a layer of a metal or alloy resistant to wear and, where necessary, corrosion, such as "Stellite", which is welded onto the seat. The layer *6a* is then surfaced and finished preliminary to securing together of the sections of the housing.

After sections *l* of the housing have been completed, in the above manner, they are disposed

in endwise alignment with the inner edges of flanges *4*, which are beveled at *4a*, closely adjacent each other and defining therebetween a V-shaped welding trough. The housing sections are then welded together and, at the same time, valve guide strips *7* are secured, by the same welding operation, to the inner faces of the sides of the housing, these guide strips being accurately positioned and held, in a suitable manner, during the welding operation.

After the sections *l* have been thus welded together, a ring *8*, comprising a bolting flange *9*, is welded to the upper end of the body of the housing, at *10*, the adjacent end of the ring and the housing body being beveled to define a V-shaped welding trough or groove, as shown. The housing can be produced in this manner with expedition and facility, and is particularly suitable for bolting to flanged pipe ends.

After the housing has been completed in the manner above described, a bonnet *11* is bolted upon flange *9* with a suitable gasket therebetween. A valve stem *12* screws through the head of bonnet *11* and operates through a suitable stuffing box in the lower portion of the bonnet, in a known manner. The lower end of stem *12* is attached to a gate valve *13* of known type, in a known manner, for relative rotation for raising and lowering the latter. A hand wheel *14* is suitably secured upon the upper end of the valve stem, and the valve *13* is provided with guides *15* which fit about the guide strips *7* for guiding the valve during operation thereof.

What I claim is:—

1. The method of producing a valve housing, which comprises forging a cup-shaped blank comprising a tubular hub provided at its upper end with an integral continuous valve seat, a housing body element extending upward beyond said seat, and a metal mass depending from the lower end of said hub, smashing down said metal mass while confining said hub against radial distortion and thereby forming an integral bolting flange extending circumferentially of the lower end of the hub and a disc closing the lower end of said hub, removing said disc and thereby completing one housing section, and disposing two housing sections so produced in endwise alignment and welding them together on approximately the transverse median plane of the resulting housing with said flanges at the ends of the housing.

2. The method of producing a valve housing, which comprises forging a housing section comprising a hub open at its upper end and closed at its lower end by a body of metal of considerable mass, smashing down said body of metal while confining said hub against distortion thereby forming at the lower end of said hub an integral circumferential bolting flange and a disc closing the lower end of said hub, removing said disc thereby completing the housing section, and disposing two housing sections so produced in endwise alignment and welding them together on approximately the transverse median plane of the resulting housing with said flanges at the ends thereof.

3. The method of producing a valve housing, which comprises forging a housing section comprising a hub open at its upper end and closed at its lower end by a body of metal of considerable mass, smashing down said body of metal thereby forming at the lower end of said hub an integral circumferential bolting flange and opening said lower end of said hub, thereby completing the

housing section, and disposing two housing sections so produced in endwise alignment and welding them together on approximately the transverse median plane of the resulting housing with said flanges at the ends thereof.

4. The method of producing a valve housing, which comprises forging a housing section comprising a tubular hub portion having a skirt at one end and a mass of metal at the other end, confining said hub and skirt so as to present a

die surface surrounding said hub in proximity to said mass of metal, smashing said mass of metal against said die surface while confining it so as to form a flange on said hub portion, and disposing two housing sections so produced in endwise alignment and welding them together on approximately the transverse median plane of the resulting housing with said flanges at the ends thereof.

JAMES HALL TAYLOR. 10
